COIN DEPOSITORY FOR ASSOCIATED
PARKING METERS

Henry P. Compton, Abilene, Tex.

Application June 23, 1947, Serial No. 756,491

4 Claims. (Cl. 232—1)

1

This invention relates to a coin depository for use in combination with parking meters, and is a continuation in part of my copending application Serial No. 689,875, filed August 12, 1946, for a Parking meter.

An object of this invention is to provide a coin depository for use in association with parking meters, which will permit a motorist after first depositing a coin in the parking meter to deposit additional coins so that an authorized person may subsequently remove one of such additional coins for deposit into the meter in order that additional parking time may be obtained without violation of the parking regulations.

In meters at present used for authorized parking along curbs, the deposit of a nickel will actuate the meter for a predetermined time period, and in the event the vehicle is to be parked for a longer period than authorized, the motorist must deposit a second or further coin which requires a return visit to the vehicle. If this return visit is delayed and an officer notices the excess parking time, the motorist is subject to a parking fine. The coin depository herein disclosed is designed to eliminate the necessity of a return visit by the motorist, by permitting the motorist to deposit two additional coins in the depository. When the officer notes that the first parking period has expired, he will look at the coin depository to see if the motorist has deposited two more coins for the privilege of parking a double time, and will then insert a key into the depository. Upon insertion of a key in the depository, one of the coins will be discharged into the hand of the officer, and the other coin will drop into the coin receiver or chamber in the depository. The discharged coin will then be deposited into the meter by the officer so as to thereby give the motorist an additional parking period without violation of the parking regulations but at double the cost of the first parking period.

With the above and other objects in view, my invention consists in the arrangement, combination and details of construction disclosed in the drawings and specification, and then more particularly pointed out in the appended claims.

In the drawings,

Figure 1 is a front elevation of a coin deposit box constructed according to an embodiment of this invention.

Figure 2 is a rear elevation, partly broken away and partly in section, of the coin box with the rear wall removed,

Figure 3 is a vertical section, partly broken away, taken on the line 3—3 of Figure 2,

2

Figure 4 is a transverse section taken on the line 4—4 of Figure 2.

Figure 5 is a rear elevation of the coin box, partly broken away and partly in section,

Figure 6 is a front elevation of the sliding plate removed from the box,

Figure 7 is a fragmentary detail section taken on the line 7—7 of Figure 2,

Figure 8 is a fragmentary section taken on the line 8—8 of Figure 2.

Referring to the drawings, the numeral 10 designates generally a coin box or depository for use with a parking meter or the like, whereby a sufficient number of coins may be deposited in this box, certain of them removable for depositing in the parking meter.

A coin box 10 is so constructed and arranged that two coins of the same denomination may be inserted in the box and upon moving of the sliding plate by an authorized person, one of the coins will be released from the box 10 for subsequent insertion into the parking meter, and the other coin will be retained within the box 10.

The coin box 10 is formed with a U-shaped or concavo-convex body 11, having side walls 12 and a front wall 14. The rear wall will be formed by a plate fixed on the standard 15 of the parking meter. The body 11 is adapted to be fixed to the standard 15 by a clamp 16 fixed to or formed on the lower end of the box 10, or other suitable fastening means.

The front wall 14 of the box 11 is provided with a pair of openings 17 through which coins may be deposited. A shield or partial cover 18 is formed on the front wall 11 about the upper end of the opening 17 to prevent moisture or dirt, or foreign articles from falling into the opening 17.

A pair of guide members as 19 and 20 are formed on the rear side of the front wall 11 along the opposite edges of the openings 17 and extending downwardly therefrom. The guide members 19 and 20 are formed of elongated bars or projections as 21, which extend below the openings 17 a short distance so that a coin may be held therebetween. Other inspection openings as 22 are formed below each of the openings 17 and covered by a transparent material as glass or plastic 24.

The windows 22 are provided for exposing the deposited coins while they are retained within the guide members 19 and 20. The box 11 is further formed with an opening as 25 through the side wall 12 below one of the guide members as 20 so that a coin may be removed therefrom.

Rabbeted channels as 26 are formed on the rear surface of the front wall 14 and a sliding plate

21 is secured between the channels 26 on the opposite sides of the front wall 14. Retaining bars or plates 28 are fixed to the front wall 14 by securing means 29, and the plates 28 engage behind the sliding plate 27 for supporting the plate 27 slidably adjacent the front wall 14. The sliding plate 27 is formed on its forward side with a pair of forwardly extending lugs 30 which are adapted to engage within the guide means 19 and 20 for holding a coin between the members 21 in the raised position of the plate 27.

When the plate 27 is lowered, the coin retaining lugs 30 are moved downwardly to a position shown in dotted lines as 31, in Figure 5, so that the coins may fall freely from the channels 19 and 20.

A coin chute as 32 is formed on the rear side of the front wall of the box 11 below one of the guide members as 20 and is adapted to guide the coin from this one guide member downwardly through the opening 25 in one of the side walls 12. The chute 32 is formed with a downwardly and outwardly extending lower wall 34. In the raised position of the plate 27 the coin is retained in the guide member 20 and as the plate 27 is moved downwardly, the coin is released from the guide member 20 and will fall into the chute 32 which is in registry with the opening 25. The retaining lug 30 in the guide 20 will then partially block the side opening 25 for retaining the coin in the chute 32. Returning the plate 27 to its raised position will move the lug 31 to its raised position permitting the coin to be discharged from the chute 32 through the opening 24. The other coin in the guide member 19 in the lower position of the plate 27 is free to fall into the lower end of the box 10.

For raising the plate 27, a cam 35 is rotatably supported in the front wall 14 and may be carried by the rotatable part of a lock 36. The cam 35 is adapted to engage with a cam follower 37 fixed to or formed on the lower end of the plate 27. Upon rotation of the lock 36 and cam 35 in a counterclockwise direction, as seen in Figure 2, the plate 27 will be raised. As the cam 35 is rotated clockwise, the weight of the plate 27 will cause it to slide downwardly into the coin releasing position.

The lock 36 is so constructed and arranged that the cam 35 will be locked in the raised position so that the plate 27 can be lowered only by the insertion of a key as 38 in the hands of a responsible person.

Since some coins are slightly misshapen after considerable use, and as the coin guides 19 and 20 are quite close fitting, it is possible that coins may become wedged in the guides. In order to clear the guides for each separate time the device is used, a dislodging lug 40 is fixed to or formed on the plate 27. The lug 40 is disposed immediately adjacent the upper edge of the openings 17 between the guide members 21 in the raised position of the plate 27 and will move down to dislodge any coins wedged between the upper end of the guide members 21 as the plate 27 moves downwardly. The cam 35 engages the follower 41 as it is moved counter-clockwise to insure a positive downward force on the plate 27 for releasing the coins.

In the use and operation of this coin box, when the person parking his car desires to park for a longer period than that allowed by the use of one coin in the parking meter, he may place two more coins into the box 10 supported adjacent the parking meter. The extra coins will be seen through the openings 22 in the front wall of the box and when the first parking period has expired, a police officer having a key 38 may remove one from the box 10 by rotating the lock 36. This coin he will place in the parking meter for the added parking period and the other coin in the box will be retained therein. In this manner a second parking period may be had at a cost of twice the original parking fee.

I do not mean to confine myself to the exact details of construction herein disclosed, but claim all variations falling within the purview of the appended claims.

What I claim is:

1. A coin deposit receptacle having a front wall, said front wall formed with a pair of similar coin openings therein, coin guide members fixed on the rear surface of said front wall adjacent said openings and extending therebelow, a sliding plate adjacent said front wall spaced therefrom by said guide members, coin retaining lugs fixed on said plate positioned between said guide members in the raised position of said plate for retaining coins therein and permitting the coins to fall therefrom in the lowered position of said plate, said receptacle formed with an opening therethrough below one of said coin openings, an operator for raising said plate, a coin chute below one of said retaining lugs, said chute registering with said latter opening, the shifting of said plate permitting the discharge of one coin from said receptacle, and the lodging of a second coin within said receptacle.

2. A coin deposit receptacle as set forth in claim 1, wherein said coin chute is fixed on said housing.

3. A coin deposit receptacle as set forth in claim 1, including a lug on said sliding plate above the center of said coin openings in the raised position of said plate for dislodging a coin between the upper end of said guide members upon lowering of said plate.

4. A coin deposit receptacle having a front wall, said front wall formed with a pair of similar coin openings therein, coin guide members adjacent said openings and extending therebelow, a sliding plate adjacent said front wall spaced therefrom by said guide members, coin retaining lugs on said plate for cooperating with said guide members for retaining coins therein in the raised position of said plate and permitting the coins to fall therefrom in the lowered position, said receptacle formed with an opening therethrough below one of said coin openings, an operator for sliding said plate, a coin chute below one of said guide members, said chute registering with said latter opening, one of said retaining lugs being disposed for retaining a coin in the said chute in the lower position of said plate and permitting the discharge of the coin therefrom in the raised position.

HENRY P. COMPTON.
